UNITED STATES PATENT OFFICE

2,512,229

CLEANOUT DOOR FOR CHIMNEY FLUES

Peter M. Glieden, Marshall, Minn., assignor to
George Graffunder, Marshall, Minn.

Application June 12, 1945, Serial No. 599,089

2 Claims. (Cl. 72—97)

1

The present invention relates to clean-out doors for chimney flues and particularly to that type which is wholly removable as contradistinguished from hinged and otherwise attached doors.

A primary object of the invention is to provide a device of the foregoing type of simpler and less expensive construction than the doors now in general use.

Another object is to provide a clean-out door which will not rust and stick and will not warp out of shape.

A further object is to provide a clean-out door and frame therefor which may be readily installed in place at the base of the chimney-flue when the chimney bricks are laid or subsequently.

Still another object is to provide a clean-out door for chimney-flues which does not require the multi-part operating mechanisms generally considered necessary in prior devices.

With the foregoing and other objects and advantages in view my invention consists of the novel construction and arrangement of parts herein disclosed and claimed.

In the accompanying drawings illustrating the invention,

Figure 1 is a front elevation of the door and frame set in place in the base of the chimney.

Figure 2 is a vertical section of door and frame on line 2—2 of Figure 1.

Figure 3 is a transverse sectional view of door and frame on line 3—3 of Figure 2.

Like numerals are used in the drawings and description to designate like parts of construction.

At the base of the chimney C and in the flue-opening F is set the flue closure consisting of a rectangular frame of suitable dimensions and a removable door conforming to the frame. 1 designates the frame and 2 the door. In the construction of both cement is preferably employed but either or both may be constructed of any other suitable material such as cast-iron. The upper and lower interior sides 3 and 4 of the opening 5 in the frame are constructed at right angles to the vertical sides of the opening and beveled or downwardly inclined, as at 6 and 7, to a point approximately midway the thickness of the frame. These beveled surfaces are disposed transversely of the opening in the frame and are formed above and below the same to create upper and lower horizontal shoulders, as at 8 and 9. The vertical sides 10 and 11 of the frame-opening are off-set, as at 12 and 13 and the shoulders 55 and lower parallel portions, the upper parallel

thus formed are beveled downwardly from front to rear at the same angle as the upper and lower beveled surfaces 6 and 7 and approximately to the same vertical plane with the horizontal shoulders 8 and 9. The door 2 is constructed in rectangular shape and its contour conforms to the opening 5 of the frame 1. It is made with sufficient thickness to allow the back to seat against the transverse shoulders 8 and 9 of the opening in the frame and the front to assume a position flush with the face of the frame. The top and bottom edges are beveled transversely to fit the upper and lower beveled surfaces 6 and 7 of the frame and produce a snug closure when the door is in place. The vertical sides or edges 14 and 15 of the door are provided with off-sets beveled and positioned to fit against the beveled shoulders 12 and 13 formed on the vertical sides of the door-frame. A hand-grasp 16 is provided on the front of the door.

In operation a complete closure of the chimney-flue is effected and the door interlocked with the frame by seating its lower beveled edge in the groove formed by the beveled surface 7 and contiguous transverse shoulder 9 of the lower part of the frame 1 and then forcing the beveled shoulders of the vertical sides of the door into engagement with the contiguous beveled shoulders at 12 and 13 on the inner vertical sides of the frame. To remove the door it is necessary merely to lift it by the hand-grasp from its seat in the said groove and at the same time give it a forward and upward pull, thereby disengaging the interlocked shoulders.

What I claim as new and desire to secure by Letters Patent of the United States is:

1. A closure for the clean-out opening of a chimney flue, said closure comprising a frame set into the clean-out opening formed with a vertically elongated substantially rectangular door opening communicating with the interior of the chimney flue, said door opening comprising a rear section and a front section, said rear section having substantially plane parallel sidewalls and top and bottom walls and being smaller in area than said front section, said front section having parallel top and bottom walls similarly rearwardly declined and of substantially the same width, said front section top and bottom walls being vertically positioned to define transverse shoulders above and below, respectively, the top and bottom walls of said rear door opening section, the sidewalls of said front section comprising upper parallel portions and lower parallel portions, the upper parallel

portions being spaced laterally outwardly from the lower parallel portions so as to define abbreviated shoulders on the upper ends of said lower parallel portions, said shoulders being rearwardly declined at substantially the same angle as said top and bottom walls of said front door opening section, and a door comprising a plate of substantially uniform thickness and of similar dimensions to said front door opening section arranged to seat conformably in said front opening section with its front face substantially flush with the front face of said frame, and its back face abutting said transverse shoulders.

2. A closure for the clean-out opening of a chimney flue, said closure comprising a frame set into the clean-out opening formed with a vertically elongated substantially rectangular door opening communicating with the interior of the chimney flue, said door opening comprising a rear section and a front section, said rear section having substantially plane parallel sidewalls and top and bottom walls and being smaller in area than said front section, said front section having parallel top and bottom walls similarly rearwardly declined and of substantially the same width, said front section top and bottom walls being vertically positioned to define transverse shoulders above and below, respectively, the top and bottom walls of said rear door opening section, the sidewalls of said front section comprising upper parallel portions and lower parallel portions, the upper parallel portions being spaced laterally outwardly from the lower parallel portions so as to define abbreviated shoulders on the upper ends of said lower

parallel portions, said shoulders being rearwardly declined at substantially the same angle as said top and bottom walls of said front door opening section, and a door comprising a plate of substantially uniform thickness and of similar dimensions to said front door opening section arranged to seat conformably in said front opening section with its front face substantially flush with the front face of said frame, and its back face abutting said transverse shoulders, said door having top and bottom walls of the same length, width, and declination as said top and bottom walls of said front door opening section, sidewalls comprising upper and lower portions conforming to said upper and lower sidewall portions of said front section opening, and declining shoulders at the lower ends of said upper sidewall portions conforming to said shoulders on the upper ends of said lower sidewall portions of said front door opening section, and abbreviated rearwardly declining portions at the sides of said door conformably engaging said abbreviated shoulders.
